UNITED STATES PATENT OFFICE.

FRANK W. MIX, OF NEW BRITAIN, CONNECTICUT.

DESIGN FOR THE ORNAMENTATION OF KEYS.

SPECIFICATION forming part of Design No. 16,564, dated March 9, 1886.

Application filed December 31, 1885. Serial No. 187,308. Term of patent 7 years.

To all whom it may concern:

Be it known that I, FRANK W. MIX, a citizen of the United States, residing at New Britain, in the county of Hartford and State of Connecticut, have invented and produced 5 a new and original Design for the Ornamentation of a Key, of which the following is a specification, reference being had to the accompanying drawing.

10 My invention relates to a design for the ornamentation of a key; and it consists in ornamental chasing or marks, either raised or depressed, formed on the barrel of the key; and it further consists in the peculiar shape of the 15 handle, which is formed with trefoil ends, its center being provided with an elongated opening having centrally-located transepts, a raised ornamental finish being formed around the edges of the opening and around the outer 20 edges of the handle, and an arc-shaped band, which forms an ornamental finish to the central portion of the edge of the handle.

The accompanying drawing represents a view of the key in perspective.

25 A represents the barrel of the key, provided with the ornamental chasing or marks a.
B represents the handle, having the trefoil

ends b, the elongated opening C, with the transepts c, the ornamental borders D and d, located around the edges of the openings C c 30 and the outer edge of the handle, respectively, and the ring-band E.

Having fully described my design, what I claim as new, and desire to secure by Letters Patent, is—

35

1. A design for the ornamentation of a key, consisting of a key-handle transverse to the barrel, and having trefoil-shaped ends and a central opening, substantially as shown.

2. A design for the ornamentation of a key, 40 consisting of a key-handle transverse to the barrel, having trefoil-shaped end, the elongated opening, and the centrally-located transepts, substantially as shown.

3. In a design for a key, the ornamentation 45 of the same, consisting in ornamental chasings or marks on the barrel thereof, and the handle transverse to the said barrel and having trefoil ends and a central opening, substantially as shown.

FRANK W. MIX.
